United States Patent Office.

WILLISTON K. FULLER, OF MODENA, ILLINOIS.

Letters Patent No. 72,474, dated December 24, 1867.

IMPROVED APPARATUS FOR VENTILATING MILLSTONES.

The Schedule referred to in these Letters Patent and making part of the same.

TO ALL WHOM IT MAY CONCERN:

Be it known that I, WILLISTON K. FULLER, of Modena, in the county of Stark, State of Illinois, have invented a new and improved Mode of Introducing a Current of Air between Millstones while running, thereby preventing the stones and flour from heating, and increasing the quantity and improving the quality of the flour made.

I do hereby declare that the following is a full and exact description thereof, reference being had to the drawings accompanying, and to the letters of reference marked thereon—

Figure 1 being a view of the upper surface of the stone.

Figure 2 a transverse section of the same, and

Figure 3 a view of the under surface.

The construction and operation of my invention are as follows: The scroll-wing A is attached to the top of the millstone, and the tapering tube B connecting with said wing, passes to and down the eye of the stone for a certain portion of its length, indicated at C, fig. 2. Entering the substance of the stone at this point at an angle, the tube opens on the under surface of the stone a short distance from the eye, in the direction of the leading furrows, as will be seen in fig. 3, E.

The working of my invention is evident. The scroll-wing A is so formed that in revolving with the stone it gathers air, which, by its rapid motion, is forced through the tube B down into the eye, and discharged between the stones in the direction of the leading furrows. The current of air thus continually forced between the stones keeps them cool, prevents moisture, increases largely the amount ground in a given time, and makes more and better flour from the same quality of wheat.

What I claim as my invention, and desire to secure by Letters Patent, is—

The millstone G, provided with the scroll-wing A and tube B, so arranged that the tube will pass down the eye of the stone a certain portion of its length, and through the corner at an angle, so as to open on the face of the stone a short distance from the eye, constructed and operating substantially as herein indicated.

WILLISTON K. FULLER.
